ELECTRICALLY SEVERING STRANDED WIRE
STRUCTUREGorman C. Burd, Adrian, Mich., assignor to
American Cable Company, Inc., New York,
N. Y., a corporation of Delaware

Application October 20, 1931, Serial No. 569,935

8 Claims. (Cl. 219—1)

This invention relates to machines for severing, by means of an electrical current, such articles as wire rope or other stranded wire structures; also wires, wire rods, and in general any metal 5 articles which may be so severed.

An object of the invention is to provide a novel method by which articles of the above description may be severed accurately and rapidly, with a minimum expenditure of labor and 10 with only the degree of skill which may be commonly expected of unskilled workmen or workmen of average mechanical training.

A more particular object of the invention is to provide a method of severing wire rope or 15 similar stranded wire structures in such a manner that the severed ends of the component wires will be compactly united metallically to constitute a terminal portion somewhat reduced in cross sectional area from the diameter of the 20 body portion of the wire rope, so that this end portion may be readily inserted into sockets of a diameter corresponding to, or closely approximating that of, the rope diameter, without the necessity for grinding or otherwise finishing the 25 terminal portion to be so fitted into the attachment.

In existing methods of cutting wire rope, etc. electrically, there has been experienced a tendency of the metal melted or softened by the 30 heating effect of the cutting current to gather and swell between the component wires adjacent to their severed portions so that a ball of metal is formed which swells to a diameter sufficiently larger than that of the rope diameter to 35 form an enlargement which will not pass into a socket of proper diameter to fit the rope which is to be attached, but must be reduced by grinding or otherwise before the rope and fitting can be connected.

40 This operation involves considerable loss of time, labor and material and interferes seriously with the successful employment of electrical cutting as a means for severing stranded wire and similar structures.

45 Another object of the invention is to provide a machine adapted to carry into effect the method briefly described above and which will be described more at length hereinafter.

The above and other features of the invention 50 are illustrated and described fully in the accompanying drawings and specification and are pointed out in the claims.

In the drawings—

55 Fig. 1 is a view in front elevation of a machine in the construction of which the invention

has been embodied and which is adapted to carry into effect the method of the present invention.

Fig. 2 is a plan view of the same.

Fig. 3 is a fragmentary detail view in side elevation of a portion of the machine. 5

Fig. 4 is a fragmentary detail view in vertical longitudinal section taken on the line 4—4 of Fig. 2, upon a larger scale, parts being broken away. 10

Fig. 5 is a fragmentary detail view, on a still larger scale, of the ends of a wire rope, after severance.

The novel method of the present invention 15 comprises the step of passing an electrical current through the wire cable, wire or other article to be severed, of sufficient volume to cause an initial heating and softening effect, while at the same time the cable is subjected to a tension sufficient to stretch the cable to a predetermined extent at a region localized at the point where severance is to be effected; then the part so stretched is held without tension and an electrical current is passed therethrough of sufficient volume to fuse the cable at the region to be 20 severed and thereby sever the same. 25

As a result of the above-described operation, each of the severed ends produced is found to present a compact terminal portion of solid metal formed by agglomerated fused portions of 30 the component wires, which are thus metallically united or welded together, each terminal portion thus formed tapering somewhat toward the end so that the diameter at the end is sufficiently less than that of the average diameter of 35 the cable or rope to facilitate easy fitting of the end into a socket or in any aperture of a diameter corresponding closely to that of the rope diameter.

By reason of the fact that no tension is exerted on the rope during the step of passing the severing current, each of the severed ends is not pointed sharply but has a diameter which may approach that of the rope diameter as closely as may be desirable, the diameter of the severed portion being controllable more or less by the degree to which the rope has been stretched during the operation of preliminary heating and stretching constituting the first step of the method above described. 40 45 50

In a now preferred embodiment of a machine adapted to carry the above-described method into effect, the part designated by the reference character 11 is the base of the machine which may be of any suitable character and contain 55

such operating instrumentalities as transformers, switches and other apparatus incidental to the structure of this type of machine which may, in general, correspond to machines of this type 5 in conventional use and need not be described in detail.

Upon the top 12 of this base are mounted two 10 clamping heads 13 and 14, of which that shown at the lefthand side of Fig. 1 is mounted in fixed position upon the table top, this head being shown in elevation in Fig. 3.

In the form selected for illustration, it comprises a plurality of uprights 15, preferably formed integrally with the table, and between 15 which is mounted a jaw 16 pivoted at 17 in a bracket 18 extending upwardly from the supporting structure, the jaw having at its free end a clamping member 19 adapted to cooperate with a similar clamping member 20 attached removably by a clamp 21 to the supporting structure and adapted to receive one or more wire cables, ropes or similar articles R which are to be severed, it being understood that the shape of 20 these clamping members may be varied according to the character of the work to be treated. Preferably the upper clamping member will be mounted pivotally as indicated at 22.

Above the clamping jaw is mounted a cam member 23 upon a short shaft 24 around which 30 the cam may be oscillated by means of a hand lever 25, the cam engaging with the upper surface of the clamping jaw which is preferably provided with an adjustable wedge-shaped plate 26, to permit adjustment for operation upon cables of different diameters.

The other clamping head 14 is composed of parts similar in all respects to those just described with reference to the clamping head 13 and which bear the same reference characters 40 and will not be again described in detail.

The clamping head 14 is, however, so mounted upon the table top that it can be moved along the axis of the wire rope or other article to be severed, for which purpose the clamping head 45 has an extended slide member 27 working on suitable guides 28 upon the table top. Its range of movement is preferably limited by a suitable adjustable stop taking the form of a threaded post 29 fixed in the slide, and passing through 50 an apertured bracket 30 extending upwardly from the supporting structure of the base 11, the post 29 being provided with nuts 31, 32, which may be set for engagement with the bracket 30 at the desired limits.

The slide may be moved by any suitable mechanism, and for this purpose the drawing shows a lever 35 fixed on a rock-shaft 33 mounted to oscillate in the bracket 30 and in a bracket 34 extending from the base 11, the lever 35 having 60 its free end connected to the slide 27 of the movable clamping head 14 (see Fig. 3) by means of a toggle-link 36 comprising eye bolts 37 and 38 joined by a turn-buckle 39 by means of which the link may be shortened or lengthened so that a given angular movement of the lever 35 will 65 result in a longer or shorter throw of the slide 27 and movable clamping head 14.

Upon the shaft 33 is mounted a lever 40 from the outer end 41 of which is suspended pivotally 70 a weight 42 by means of a rod 43. The lower end of the rod is preferably connected to a treadle 50 mounted pivotally upon a fulcrum bracket 51 supported on the floor or on any other suitable support, the lever having a pedal 52 by means of which the operator may raise the

weight and cause upward movement of the arm 40 of the lever from which the weight is suspended, thereby causing the slide 27 and movable clamping head 14 to approach the fixed clamping head in the manner already described, until stopped by the nuts 32, as in Fig. 2.

The lever 40 is also provided with means adapted to control the turning on and off of the electrical current by a suitable switch actuated by an arm 53 which may conveniently be constituted by an extension of the arm 40 carrying the weight 42, and is so illustrated in the instance now under description.

For this purpose the arm 53 is provided with a set screw 54 adapted to be engaged with a lever 55 mounted pivotally at 56 upon the outer wall of the base 11, the free end of the lever 55 extending across a plunger 57 which constitutes the controlling means for an electrical switch 15 preferably contained within the base 11 and which may be of any form suitable to cause the 20 current to be turned on and off at will when operated by the lever 55, the form of switch being immaterial and so not requiring description, as any suitable conventional form may be 25 used for the purpose.

For the purpose of the present description it is sufficient to understand that when the foot pedal 52 is released, the weight 42 causes downward movement of the arm 40 and upward 30 movement of the arm 53 and the set screw 54, releasing the lever 55 and the switch plunger 57, whereupon the switch closes connections suitable to cause passage of current. When the treadle 52 is depressed and the weight is raised 35 the lever controlling the switch plunger 57 is forced downwardly by the screw 54 and the current is cut off.

In the operation of the machine above described the end of a wire cable or other article 40 to be severed, or an end of each of several cables, indicated by the reference character R, and which may be derived from any suitable stock supply, is led between the clamping jaws and extended along the machine until it is of the 45 desired length to be severed. It may be advantageously engaged with a stop 58 mounted upon an extension 59 of the bracket 34 carried by the machine base 11.

The handle 25 of the fixed clamping head 13 50 is then raised into the position shown in Figs. 1, 2 and 3 which results in firmly clamping the cable in the fixed clamping head.

The movable clamping head 14 is then moved, while still open, into the position shown in Fig. 1, which may be effected by pressing down upon the foot pedal 52, thus raising the weight 42 and straightening the toggle-link 36, so that the slide 27 and its clamping head 14 are moved toward the fixed clamping head into the position shown in Fig. 1, and then the handle 25 of the movable clamping head is raised and the clamping jaws are secured upon the cable or other article to be severed, the cable thus being clamped at a distance from the fixed clamping head suitable to leave between the clamping heads a portion of stock r which can be stretched to proper length to permit the desired severing action of the current.

This length of the portion r will, of course, vary according to the nature of the stock under treatment and the character of severed ends which it is desired to produce. In the instance shown, a portion of stock r of about one quarter 70 75

of an inch in length is left between the clamping heads.

It is also to be understood that these clamping heads are suitably insulated from each other, and suitably connected to the source of electrical current, such connections not requiring description nor special illustration, as they are well known in the art, this portion of the apparatus being of conventional construction 10 in the instance illustrated.

In pursuance of the method of the present invention, when the cable stock is being clamped in place, as just described, by the operation of depressing the treadle, this operation causes the 15 electrical switch to be held open as already indicated so that no current is passing while the cable is being clamped.

The operator then releases the foot pedal which permits the weight to descend, breaking 20 the toggle and causing a tension to be exerted upon the portion of cable between the clamping heads. At the same time the slight lost motion of the rock-shaft 33, preliminary to the breaking of the toggle, permits sufficient movement of the lever arm 53, and of the set screw 25 54 and lever 55 controlling the switch 57, to release the switch, and current is thus allowed to pass through the portion of cable r between the electrodes of the clamping heads.

As this section between the electrodes becomes 30 hot and soft, the tension exerted by the weight 42 rocks the shaft 33, breaks the toggle 36, and the ensuing movement of the slide 27 and clamping head 14 stretches the cable. The slide moves 35 to the right until the stop nuts 31 reach the fixed bracket 30 and after this point is reached there is no tension on the cable, the tension or load being carried or held by the stop nuts against the fixed bracket.

All this is done before the cable has had time 40 to become melted. At this step of the method the section of cable between the heads presents the appearance shown in Fig. 4 of the drawings. That is to say, its diameter is reduced precipitately from the original rope diameter and is joined with the rope portions on each side by conical tapering regions as indicated.

The next step in carrying the method into effect is to apply a melting current sufficient to 50 cause severance electrically of the cable by melting the same at the region of reduced diameter.

As soon as this portion of the cable reaches the melting point, a few sparks fly and the cable is severed, a space of about one-sixty fourth of 55 an inch being left between the two ends.

These ends now present the appearance shown in Fig. 5 which is shown upon an enlarged scale and from which it will be seen that each end has a terminal portion composed of the solidified metal which has been fused from the component strand wires and which extend approximately at right angles to the longitudinal axis of the cable, tapering gradually to the body diameter of the cable.

Such a terminal may be readily introduced 60 into any socket or aperture of a fitting with which it is desired to connect this end of the cable. This terminal may have a small crater or be slightly concave without interference with its 65 usefulness.

The operation of the novel method disclosed thus results in the formation of a cable section which, in the instance illustrated, is marked R' and which has at each end a terminal of 75 the character shown in Fig. 5, it being under-

stood that the operation above described may be repeated as long as the stock holds out, each severed portion of stock R' being finished at each end in the manner described.

It is to be noted that there is absolutely no tension on the cable at the time the cable becomes molten during the severing operation and it is found in practice that by the preliminary heating and stretching operation under tension, followed by the passage of a severing current while the cable is not under tension, the desired result is achieved of producing a clean solid cable terminal, tapering sufficiently for the desired purpose of introducing the same to the socket of a fitting with which it is to be connected, it being understood that this is but one applied use of the product, which is susceptible of many advantageous uses other than that just described.

I claim:

1. The method of severing an article of the class described which comprises the steps of holding a restricted portion of said article under tension and passing through said restricted portion an electrical heating current until said portion is softened, stretching said soft portion until it is reduced in diameter locally, then passing a melting current through the said localized region of reduced diameter while holding said portion free from tension until said article is severed at that region.

2. The method of severing a stranded wire structure of the class described which comprises the steps of holding a restricted portion of said article under tension and passing through said restricted portion an electrical heating current until said portion is softened, stretching said soft portion until it is reduced in diameter locally, then passing a melting current through the said localized region of reduced diameter while holding said portion free from tension until said article is severed at that region, said method resulting in the formation of a terminal on each side of the region of severance, each such terminal having its component wires connected by a mass of fused metal smaller in diameter than that of the cable stock and connected with the body portion of the cable by a portion tapering toward the end.

3. The method of severing a stranded wire structure of the class described which comprises the steps of holding a restricted portion of said article under tension and passing through said restricted portion an electrical heating current until said portion is softened, stretching said soft portion until it is reduced in diameter locally, then passing a melting current through the said localized region of reduced diameter while holding said portion free from tension until said article is severed at that region, said method resulting in the formation of a terminal on each side of the region of severance, each such terminal having its component wires connected by a mass of fused metal smaller in diameter than that of the cable stock and connected with the body portion of the cable by a portion tapering toward the end, said end being of substantial area and substantially at right angles to the longitudinal axis of the cable.

4. In a machine for electrically severing stranded wire articles such as cable, rope or strand, clamping devices adapted to engage the article to be severed at selected regions spaced on each side of the region of severance, and means to supply electric current to the portion

- of said article between said clamping devices; means to cause relative movement between said clamping devices thereby to apply tension to the portion of said article therebetween; means to control the flow of electrical current to said article, whereby current may be caused to flow to said portion to initially heat and soften the same and thereby to facilitate elongation thereof under said tension and reduction in its diameter, and to subsequently melt and sever said portion; and means for limiting said relative movement of the clamping devices whereby said portion will be held free of tension while it is being severed.
5. In a machine for electrically severing stranded wire articles such as cable, rope or strand, clamping devices adapted to engage the article to be severed at selected regions spaced on each side of the region of severance, and means to supply electric current to the portion of said article between said clamping devices; one of said clamping devices being movable in the direction of the axis of the rope; means adapted to urge said movable clamping device away from said other clamping device, thereby to apply tension to the portion of said article between said clamping devices, means to control the flow of electrical current to said article, means to limit the extent of tension applied to said article, and connections between said tensioning devices and said current controlling devices, whereby current is caused to flow to said portion to be severed, to heat and thus to soften the same and facilitate elongation thereof by the application of tension thereto and thereby to cause reduction in its diameter until the predetermined range of separation of said clamping heads is reached; said means being adapted also to cause flow to said elongated and constricted portion of current sufficient to melt and sever said portion, while it is held without tension, said connections also serving when operated manually in reverse direction to cause approach of said clamping devices toward each other at times against the urge of said clamp-separating means, and at the same time to cut off the flow of current.
6. In a machine for electrically severing stranded wire articles such as cable, rope or strand, clamping devices adapted to engage the article to be severed at selected regions spaced on each side of the region of severance, and means to supply electric current to the portion of said article between said clamping devices; one of said clamping devices being movable in the direction of the axis of the rope; means tending constantly to urge said movable clamping device away from said other clamping device, thereby to apply tension to the portion of said article between said clamping devices, means to control the flow of electrical current to said article, means to limit the extent of tension applied to said article, and manually operated connections between said tensioning devices and said current controlling devices, whereby current is caused to flow to said portion to be severed, to heat and thus to soften the same and facilitate elongation thereof by the application of tension thereto and thereby to cause reduction in its diameter until the predetermined range of separation of said clamping heads is reached; said means being adapted also to cause flow to said elongated and constricted portion of current sufficient to melt and sever said portion, while it is held without tension, said connections also serving when operated manually in reverse direction to cause approach of said clamping devices toward each other at times against the urge of said clamp-separating means, and at the same time to cut off the flow of current.
7. The method of severing an article of the class described, which comprises the steps of heating to plasticity a definite short length of the same, at the same time stretching the said definite short length as it assumes a state of plasticity to an extent short of pulling it apart, then, without further elongation of the said length, applying to it sufficient heat to fuse it in the region of its smallest diameter.
8. The method of severing an article of the class described, which comprises the steps of passing an electric current through a definite short length of the same, at the same time stretching the said length as it softens under the influence of the current to an extent short of pulling it apart, then, without further elongation of the said length, passing through it a current sufficient to fuse it in the region of its smallest diameter.

GORMAN C. BURD. 50
